STACKABLE TOTE BOX

Ralph C. Fritz, Jr., Van Nuys, Godfrey L. dé Caccia, Culver City, and Darrell Ratzlaff, Los Angeles, Calif.

Application January 21, 1953, Serial No. 23,244

Term of patent 14 years

(Cl. D58—13)

To all whom it may concern:

Be it known that we, Ralph C. Fritz, Jr., Godfrey L. dé Caccia, and Darrell Ratzlaff, citizens of the United States of America and residents of Van Nuys, Culver City, and Los Angeles, respectively, in the county of Los Angeles and State of California, have invented a new, original, and ornamental Design for a Stackable Tote Box, of which the following is a specification, reference being had to the accompanying drawing, forming a part hereof.

Fig. 1 is a perspective view of a stackable tote box, showing our new design;

Fig. 2 is a plan view thereof; and

Fig. 3 is a side elevational view thereof.

We claim:

The ornamental design for a stackable tote box, as shown.

RALPH C. FRITZ, JR.
GODFREY L. DÉ CACCIA.
DARRELL RATZLAFF.
